COLLAR PROTECTOR

John M. Darling, Kansas City, Mo.

Application February 2, 1948, Serial No. 5,742

6 Claims. (Cl. 223—83)

1

The present invention relates in general to shirt collar protectors and it deals more particularly with temporary protectors of the type applied to laundered shirts having attached collars to prevent the collars from being deformed or otherwise injured prior to the time the shirt is worn.

Collar-supporting devices of this general character are well-known and widely used by commercial laundries to reinforce collars so that they will not be crushed, wrinkled, creased or otherwise collapsed when a plurality of shirts are bundled or wrapped together. They also are used to a considerable extent in new shirts to keep the collars attractive during the handling that normally occurs in merchandising.

Broadly speaking, it is the object of the present invention to provide an improved collar protector of this character. More specifically, it is the object to provide a device that not only performs the normal reinforcing functions but also protects a part of the collar which is exceedingly vulnerable to injury but which heretofore has been unprotected.

The body of a shirt can be folded into a flat rectangle and customarily is so folded after laundering or during merchandising; however, due to its cut and the way it is fitted into the body of the shirt, the collar necessarily projects above the balance of the shirt making reinforcement thereof necessary to prevent crushing as aforementioned. Moreover, because the collar projects in this fashion the upper edge of the collar, particularly around its forward half, is the surface most likely to engage adjoining objects. As a result, when shirts are bundled together and shifted relative to one another, it is this edge that bears the brunt of the abrasive or wearing action. Similarly, when the shirt is packaged in a box it is this marginal edge which rubs against the inside of the box and hence is first to become soiled or worn. Again when the top shirt in a chest drawer rubs against the bottom of the drawer above as a result of one or the other drawer being pushed in or out, it is mainly the edge of the collar which suffers.

Accordingly, an important object of the invention is to protect this particularly vulnerable region of the collar and toward this end I provide a lip or ledge on my protector which overhangs the entire forward rim of the collar.

Other objects and features will appear in the course of the following description of the invention.

In the accompanying drawings which form a 55 face of the neck band; the latter operation forces

2

part of the specification and are to be read in conjunction therewith, and in which like reference numerals are employed to indicate like parts of the various views,

5 Fig. 1 is a perspective view of the upper portion of a folded shirt showing my improved collar protector in position,

Fig. 2 is a plan view of the protector showing same in flat or unfolded condition,

10 Fig. 3 is a cross sectional view taken along the line 3—3 of Fig. 1 in the direction of the arrows, and

Fig. 4 is a cross sectional view taken along the line 4—4 of Fig. 1 in the direction of the arrows.

15 My collar protector is made of flat sheet material having sufficient flexibility to permit longitudinal flexing, cardboard being preferred because of its low cost and because of the ease with which it can be stamped or cut with dies into 20 the desired form.

The form of the protector can readily be appreciated from Fig. 2. In outline it has arcuate longitudinal edges 10 and 12 and straight parallel lateral edges 14 and 16.

25 Extending inwardly from the opposite lateral edges along the line approximately parallel to the forward edge 12 are slits 18 which, as they near one another, curve downwardly and then return diagonally upward and away from one another as shown at 20. These slits divide the form into 30 a forward band 22 and a rear band 24 connected to one another by the narrow tapered throat section 26. The throat section is weakened by a short incision 28.

35 On a line paralleling each slit 18 are a pair of longer incisions 30 and 32 which with the aforesaid slits define a narrow intermediate band 34 terminating adjacent the throat section in a pointed tab 36; this intermediate band is connected to the rear band 24 at three points indicated by the numeral 38.

In applying my collar protector to a shirt the opposite halves of band 22 are bent rearwardly and the free ends pinched toward one another 45 with the thumb and finger of one hand until they are close enough together to be inserted beneath forward edges of the flap 40 of the collar. Thus inserted the central portion of band 22 is pushed toward the collar advancing the ends of the band around the sides until the entire band is disposed flat against the neck band 42 and under the folded-down flaps 40 as shown in Fig. 1. Then the band 24 is swung rearwardly and downwardly inside the collar where it conforms with the inner 50 55 face of the neck band; the latter operation forces

the material at points 38 to fold so that the narrow band 34 assumes a position over the upper folded edge or rim of the collar covering and protecting approximately the forward half thereof.

Thus, it will be seen that my device supports and reinforces the collar to maintain the shape thereof until worn and at the same time shields the forward rim of the collar. As previously pointed out, this is the portion of the shirt most frequently soiled or injured during storage due to contact with other objects and such protection therefore is very important. When shirts provided with my protector are stacked one on top of another or crowded into a carton or drawer the physical contact or pressure which otherwise would be concentrated on the narrow rim of the collar is instead placed on the protective bands 34. Similarly, when shirts are stored in a drawer the protective bands prevent the collar of the top shirt from rubbing against the bottom of the drawer above as would otherwise be the case. Other common instances of soiling or abrasion of the shirt collar likewise are prevented.

From the foregoing it will be seen that this invention is one well adapted to attain all of the ends and objects hereinbefore set forth together with other advantages which are obvious and which are inherent to the structure.

It will be understood that certain features and subcombinations are of utility and may be employed without reference to other features and subcombinations. This is contemplated by and is within the scope of the claims.

Inasmuch as various embodiments of the invention may be made without departing from the scope thereof, it is to be understood that all matter herein set forth or shown in the accompanying drawings is to be interpreted as illustrative and not in a limiting sense.

Having thus described my invention, I claim:

1. In combination with a shirt having an attached collar, a collar stiffener and protector comprising a pair of collar bracing bands of flexible stiffening material conformable to the inner and outer faces of the collar neck band, a flexible connection between the mid portions of the bracing bands, and a pair of arcuate ledge members on the inner bracing band overhanging the upper edge of the collar on either side of the junction between the ends of the collar, said ledge members attached solely to the inner bracing band and having their adjoining ends free of the connection between the inner and outer bracing bands.

2. A combination as in claim 1 wherein each ledge member is attached to the inner bracing band at a plurality of spaced points.

3. A collar stiffener and protector for collar attached shirts, comprising an elongated sheet of flat flexible stiffening material having a pair of

short slits spaced side by side at substantially the center of the sheet, each slit being approximately aligned with the short axis of the sheet, said sheet also having a pair of long slits each beginning at one end of one of said short slits and extending outwardly therefrom approximately along the longitudinal axis of the sheet to the end of the sheet, said sheet being weakened along a line beginning at the other end of each short slit and extending parallel to the long slit substantially to the end of the sheet.

4. A combination as in claim 3 wherein said sheet is weakened along a line between and transverse to said short slits.

5. A collar stiffener and protector for collar attached shirts, comprising an elongated sheet of flat flexible stiffening material having a pair of short slits spaced side by side at substantially the center of the sheet, each slit being approximately aligned with the short axis of the sheet, said sheet also having a pair of long slits each beginning at one end of one of said short slits and extending outwardly therefrom approximately along the longitudinal axis of the sheet to the end of the sheet, said sheet having a series of slits disposed end to end along a line beginning at the other end of each short slit and extending parallel to the long slit substantially to the end of the sheet.

6. A collar stiffener and protector formed from a blank of sheet material; said blank having substantially parallel, longitudinally curved front and rear edges and comprising a front section extending longitudinally of the blank from end to end, a rear section extending longitudinally of the blank from end to end, a neck aligned with the short axis of the blank connecting the mid-portions of said front and rear sections, and intermediate longitudinal sections on either side of said neck extending from the neck to opposite ends of the blank between said front and rear sections; said blank being slit inwardly from opposite ends along a longitudinal line between said intermediate sections and said front section; the innermost end of the slits continuing rearwardly along the sides of said neck to said rear section; and said blank being weakened along a longitudinal line separating said intermediate sections from said rear section.
